Law Offices of Brian S. Steinberger, PA(57) **CLAIM**

The ornamental design for an armored truck, as shown and described.

DESCRIPTION

FIG. 1 is an upper front left perspective view of the novel armored truck.

FIG. 2 is an upper rear right perspective view of the armored truck of FIG. 1.

FIG. 3 is a left side view of the armored truck of FIG. 1.

FIG. 4 is a right side view of the armored truck of FIG. 1.

FIG. 5 is a front side view of the armored truck of FIG. 1.

FIG. 6 is a rear side view of the armored truck of FIG. 1; and,

FIG. 7 is a top view of the armored truck of FIG. 1.

The broken lines in FIGS. 1-6 are for purposes of illustrating portions of the armored truck that form no part of the claimed design.
